UNITED STATES PATENT OFFICE.

IRA E. McCABE, OF CHICAGO, ILLINOIS.

PRESSURE-ACTUATED CIRCUIT CONTROL.

Application filed February 11, 1922. Serial No. 535,755.

This invention comprises a pressure actuated circuit control. It is contemplated among the objects of the invention, to associate in compact and accessible arrangement, 5 pressure responsive apparatus adapted to be associated with a source of varying pressure; the pressure responsive apparatus may include a high pressure and a low pressure device and connections adapted to register 10 differential pressure; to associate with such devices a liquid contact circuit control, in the present instance shown in the form of a tube, within which the terminals of a circuit are sealed and containing an inert gas for 15 the purpose of quenching any spark and mercury as the medium through which the circuit is opened and closed.

Another object is to arrange these devices within a closure where they will be closed 20 off from dust, moisture and any foreign substances which might interfere with their perfect working; wherein the component parts may be readily seen and easily reached for adjustment or repair; and wherein the 25 carrier for the circuit closing device will lend itself to a variety of uses and various combinations of switch or circuit control in association with the pressure devices so that a large and varied class of uses is provided. Other objects and advantages will 30 be in part apparent, and in part brought out more fully in the description which follows.

An embodiment of the invention is shown in the accompanying drawing, the following 35 views being shown:

Fig. 1, is a view in front elevation, partly broken away, and parts being shown in section of a device embodying my invention;

Fig. 2, is a view in vertical section on line 40 2-2, of Fig. 1;

Figs. 3 and 4 are detail views in section of the circuit control device in open and closed position.

In these views, 1 is a casing of the gauge 45 type, closed in front by a removable glass which permits access to an interior for housing the working parts, and through which they may be seen. Passing through an opening in the casing there is a nipple for 50 connection to a source of variable pressure,

and a hollow inwardly extending portion 2, of the nipple secured suitably to the casing constitutes a support and connecting medium for bringing pressure to devices now to be described. The means for securing the nipple to the casing, as here shown comprise outwardly extending portions secured to the casing as by screws.

Disposed on the support 2 there are hollow tubes 3 and 4 of the Bourdon variety, closed 60 at their outer ends and in communication, through their hollow interiors with the source of pressure. These may be arranged to respond equally to the influence of pressure or one may be connected directly to a 65 high and the other to a low by direct connection for each tube in a well known manner, instead of the single source of supply here shown. These constitute pressure responsive devices the movements of which, 70 due to variations of the pressure, are utilized to perform functions the manner of which and the structure utilized will now be explained.

The outer end of one of the tubes carries 75 a support, in the form of a loop or bridge 5 for an adjusting instrumentality comprising oppositely disposed screws 6 and 7, threaded into openings placed at opposite sides of the arms of the loop or support. 80 The outer end of the other tube carries a support 8 for a pin, axle or fulcrum 9. Mounted for swinging movement upon this pin and intermediate their ends, there are arms 10, in spaced relation and connected 85 at their upper ends by a friction and bearing pin 11. The other end of the arms has an insulated carrier 12 adjustably mounted between the arms and constitutes a support 90 for a circuit controlling instrumentality 13.

This as here shown, is in the form of a hollow tube within which are fused terminals 14 and 15 in communication with lead wires 16 and 17. These are connected, as by posts 18 and 19, with leads extending from binding posts 20 suitably mounted on the casing and insulated therefrom. The tube is hermetically sealed and contains an inert gas to quench sparking and a drop 21, of suitable liquid such as mercury, is utilized to 100

make and break the circuit. The two positions are indicated clearly in Figs. 3 and 4.

The arms 10 constitute a lever of the first class carrying at their free ends a support for a circuit control, which is in the nature of a pendulum, and the sweep and tension or resistance to the action of the tubes 3 and 4 is regulable through the adjusting screws 6 and 7. The fulcrum 9 being a fixed point at the initial adjustment of the device, if the bearing pin 11 is moved to the left of Fig. 1, for instance, the free end of arms 10, carrying the circuit control will be swung to the right. This is accentuated by the placing of the fulcrum nearer the upper end of the arms. In this way the distance through which the circuit control device will have to travel before the mercury reaches the position shown in Fig. 4, can be regulated at will and the same adjustment is capable with its movement in the opposite direction.

After the adjustment of the screw 6 or 7 has been made to limit the sweep of the arms, the other screw may be turned against the bearing pin to place a tension on the pin and offer resistance to the spreading of the tubes 3 and 4. This constitutes an adjustment for the pressure. Means are provided for permitting access to the adjusting screws 6 and 7 from the outside of the casting, and as here shown comprise threaded openings in alignment with the screws and closed by screw plugs 22. These may be sealed against tampering.

The device is shown in neutral position in Fig. 1. Spreading of the outer ends of the Bourdon tubes due to pressure will swing the free ends of arms 10 to the right and cause the circuit control to assume the position shown in Fig. 3. Reduction of the pressure beyond a predetermined point will swing the free ends of the arms 10 to the left of Fig. 1, causing the mercury to make contact between the contact devices and close the circuit. By utilizing circuit control devices having a larger number of contact devices several circuits can be controlled at the same time, it being merely necessary to place in the carrier 12 a circuit control suitable to the particular use required. The adjustment of the sweep and starting point of the free ends of the arms and the tension on the bearing pin permit a wide range of adjustments adapted to a large variety of uses.

While the invention has been disclosed in the embodiment herein shown, it will be understood that many changes in the construction and arrangement are contemplated as being within the scope of the invention as set forth in the claims.

What I claim is:

1. A pressure actuated circuit control comprising a pressure responsive instrumentality; a carrier for a liquid contact circuit

opening and closing device; a fulcrum associated and movable with said pressure responsive instrumentality on which said carrier is mounted for oscillating movement; a liquid contact circuit opening and closing device operatively associative with the carrier; and means co-acting with the pressure responsive instrumentality to oscillate the carrier; said mechanism including a yoke member connected at one point to the pressure responsive instrumentality and at another point to the carrier.

2. A pressure actuated circuit control comprising a pressure responsive instrumentality; a carrier for a liquid contact circuit opening and closing device; a fulcrum associated and movable with said pressure responsive instrumentality on which said carrier is mounted for oscillating movement; a liquid contact circuit opening and closing device operatively associative with the carrier; and mechanism connecting the pressure responsive instrumentality directly to the carrier; said mechanism including a yoke member, connected at one point to the pressure responsive instrumentality and at another point to the carrier, and mechanism for changing the position of a portion of the carrier with relation to the pressure responsive instrumentality to vary the oscillatory movement of the carrier.

3. A pressure actuated circuit control comprising a pressure responsive instrumentality; a carrier for a liquid contact circuit opening and closing device; a fulcrum on which said carrier is mounted for oscillating movement; a liquid contact circuit opening and closing device operatively associative with the carrier; mechanism connecting the pressure responsive instrumentality directly to the carrier; said mechanism including a yoke member connected at one point to the pressure responsive instrumentality and at another point to the carrier; mechanism for changing the position of a portion of the carrier with relation to the pressure responsive instrumentality to vary the oscillatory movement of the carrier; said mechanism including an adjusting instrumentality forming a part of the connection between the yoke and carrier.

4. A pressure actuated circuit control comprising pressure responsive instrumentality; a bearing for a swinging arm operatively associated with the pressure responsive instrumentality; means associated with the arm and pressure responsive instrumentality for imparting movement to the arm; a liquid contact circuit controlling device connected with the arm and actuatable thereby to open and close a circuit; means for offering resistance to the movement of the arm on the bearing; said means including a clamping instrumentality adapted to be adjustably associated with a portion of the arm.

5. A pressure actuated circuit control comprising a pressure responsive instrumentality; a carrier for a liquid contact circuit opening and closing device; a fulcrum on which said carrier is mounted for oscillating movement; a liquid contact circuit opening and closing device operatively associable with the carrier; mechanism connecting the pressure responsive instrumentality directly to the carrier; and mechanism for varying the resistance of the carrier to movement whereby the amount of pressure required to move the carrier may be adjusted.

6. A pressure actuated circuit control comprising a pressure responsive instrumentality; a carrier for a liquid contact circuit opening and closing device; a fulcrum on which said carrier is mounted for oscillating movement; a liquid contact circuit opening and closing device operatively associable with the carrier; mechanism connecting the pressure responsive instrumentality directly to the carrier; and mechanism for varying the resistance of the carrier to movement whereby the amount of pressure required to move the carrier may be adjusted; said mechanism comprising a friction member connected with the carrier and clamping mechanism carried by the yoke and connected with the friction member.

7. A pressure actuated circuit control comprising a pressure responsive instrumentality; a carrier for a liquid contact circuit opening and closing device; a fulcrum on which said carrier is mounted for oscillating movement; a liquid contact circuit opening and closing device operatively associable with the carrier; mechanism connecting the pressure responsive instrumentality directly to the carrier; and mechanism for varying the resistance of the carrier to movement whereby the amount of pressure required to move the carrier may be adjusted; said mechanism comprising a friction member connected with the carrier and clamping mechanism carried by the yoke and connected with the friction member; said clamping mechanism including a screw threaded into a portion of the yoke and bearing against the friction member.

8. A pressure actuated circuit control comprising a pressure responsive instrumentality; a fulcrum for an arm operatively associated with a portion of the pressure responsive instrumentality; an arm having a swinging movement on the fulcrum; a liquid contact circuit controlling instrumentality operatively associated with the arm whereby movement of the arm will operate the liquid contact instrumentality to open and close a circuit; a connection between another portion of the arm and a portion of the pressure responsive instrumentality whereby variations in pressure will impart movement to the arm; and means for varying resistance to the movement of the arm due to variations of pressure.

9. A pressure actuated circuit control comprising a pressure responsive instrumentality; a fulcrum for an arm operatively associated with a portion of the pressure responsive instrumentality; an arm having a swinging movement on the fulcrum; a liquid contact circuit controlling instrumentality operatively associated with the arm whereby movement of the arm will operate the liquid contact instrumentality to open and close a circuit; a connection between another portion of the arm and a portion of the pressure responsive instrumentality whereby variations in pressure will impart movement to the arm; means for varying resistance to the movement of the arm due to variations of pressure; said means including a member connected with the pressure responsive instrumentality and arm; and an adjustable friction device operatively associated with the member and arm.

10. A pressure actuated circuit control comprising a Bourdon tube; a yoke on an end thereof; a second tube; a bearing thereon; an arm mounted for swinging movement on the bearing; a liquid contact circuit controlling instrumentality operatively associated with the arm; and an adjustable connection between the yoke and a portion of the arm.

11. A pressure actuated circuit control comprising a Bourdon tube; a yoke on an end thereof; a second tube; a bearing thereon; an arm mounted for swinging movement on the bearing; a liquid contact circuit controlling instrumentality operatively associated with the arm; an adjustable connection between the yoke and a portion of the arm; and means carried by the yoke for imparting a frictional resistance to movement of the arm.

12. A pressure actuated circuit control comprising a plurality of pressure responsive devices; a carrier for a liquid contact circuit control pivotally mounted for swinging movement on one of the pressure responsive devices to constitute a fulcrum; a liquid contact circuit opening and closing device operatively associated with the carrier; mechanism connecting the carrier and another of the pressure responsive devices whereby movement of either of the pressure responsive devices will oscillate the carrier; and mechanism for adjusting the position of the carrier with relation to one of the pressure responsive devices to regulate the oscillatory movement of the carrier.

13. A pressure actuated circuit control comprising a plurality of pressure responsive devices; a carrier for a liquid contact circuit control pivotally mounted for swinging movement on one of the pressure responsive devices to constitute a fulcrum; a liquid

contact circuit opening and closing device operatively associate with the carrier; mechanism connecting the carrier and another of the pressure responsive devices whereby movement of either of the pressure responsive devices will oscillate the carrier; and mechanism for adjusting the position of the carrier with relation to one of the pressure responsive devices to regulate the

oscillatory movement of the carrier; said 10 mechanism comprising a member connecting one of the pressure responsive devices and the carrier; and a screw disposed on the member and connecting with the carrier.

In testimony whereof I affix my signature.

IRA E. McCABE.
